UNITED STATES PATENT OFFICE.

SIDNEY C. CLARK, OF PORT CLINTON, OHIO, ASSIGNOR TO AMERICAN GYPSUM COMPANY, OF PORT CLINTON, OHIO, A CORPORATION OF OHIO.

PROCESS OF MANUFACTURING WALL BOARD.

Application filed September 23, 1925. Serial No. 57,997.

This invention relates to improvements in processes for making plaster or wall board and more particularly to a method for treating the product to obtain a strong and perfectly square edge.

Wall board, as commonly known, is a composition wall covering or building material consisting of a layer of plaster or stucco, interposed between covering sheets of paper, of a special grade for the purpose. This material is usually about three-eighths of an inch in thickness and is put on the market in various widths from 32 to 48 inches, and in lengths from 6 to 12 feet. The most extensive use for wall board is the finishing of interior walls, and ordinarily takes the place of lath and plaster, being nailed directly to the studding or to furring strips, and the surface decorated.

The chief difficulty experienced in the use of wall board, is the concealing of the joints between the boards, especially where a decorative coating is applied directly to the surface of the board. Various expedients have been adopted to overcome this difficulty, such as wood panel strips, crack filler, and tape, but none of these are wholly satisfactory since it has been found to be practically impossible to eliminate unevenness at the abutting edges of the board. One of the chief causes for this condition is the extensive use of what is known as a covered edge type of wall board, in which the margins of the covering sheets are folded over the side edges to cover the plaster body. Experience has shown that the folding of the paper over the edges makes it practically impossible to produce a perfectly square and true edge, first because paper cannot be folded to a sharp corner and secondly, because in the process of manufacture it is difficult, if not impossible, to control the materials so that the edges of the finished board are perfectly true.

It follows, therefore, that while the sealing or covering of the edge makes for a more substantially and durable product for shipment and handling, this advantage is offset by the unevenness of the edges, so that it is ordinarily impossible to apply the board edge to edge with any degree of certainty that the joints will either be flush or the cracks uniform. In short, whatever merit which may be claimed for a covered edge board, extends only to the protection afforded dur-

ing transit, but thereafter becomes a source of difficulty, if not a practical disadvantage. With improvements in methods of shipment and intelligent handling of the product, it is conceived that an actual covering of the stucco at the edges is not as essential as once regarded, and therefore may be dispensed with, for the sake of trueness of edge. However, it is deemed desirable to reinforce (as distinguished from covering) the edge of the board, both to prevent cracking and disintegrating at the edges during shipment, and to provide a stronger edge through which nails may be driven.

I have therefore conceived a type of plaster or wall board which is essentially a reinforced edge board, so that it will have ample marginal strength to withstand shipment, and yet have uniformly true and even edges, so that a perfectly flush joint will be made when the boards are applied edge to edge on a wall.

This process or method of treatment will now be disclosed, with the aid of the accompanying drawings, in which

Figure 1 is a perspective view of a piece of plaster board showing the preferred type of edge, prior to the final process.

Figure 2 is a view similar to Figure 1, showing the finished product.

Figure 3 is a view in side elevation of a suitable apparatus for processing the board in accordance with the invention.

Figure 4 is a top plan view of the apparatus.

Figure 5 is an enlarged top plan view of one of the grinding elements of the apparatus.

Figure 6 is an enlarged view in elevation of the grinding element as taken on line 6—6 of Figure 5, and

Figure 7 is an enlarged detail view showing the action of the grinding wheel on the edge of the board.

The most desirable form of plaster board susceptible of treatment by the process of my invention is that disclosed in my previous application, filed Feb. 5, 1923, Serial No. 616,973 and herein shown in Figure 1. This type of board consists of the usual layer or body of stucco 1, with the covering sheets 2, 2, extending over the faces of the stucco. The margins 2^a of the covering sheets are carried to the side edges of the body, thence folded over the side or edge faces for a short

distance and thence folded again at right angles straight back into the body 1, substantially midway between the top and bottom with a thin layer of stucco therebetween. Thus, there is formed along each side edge, a margin consisting of four thicknesses or plies of paper separated by layers of stucco of substantially uniform thickness. In practice, however, it has been found difficult to control the materials so that the margins of the paper are turned in at just the desired point in the body or with a uniform thickness of stucco between. Particularly is it difficult, if not impossible, to secure a sharp bend either at the point where the paper is first folded over the edge or where it enters the body, in fact, the very nature of the paper is such that rounded edges invariably result. Moreover, it is often difficult to control the flow of stucco between the folded in edges of the paper so that in some instances a groove will be formed and again it will be forced out between the folds, and spread unevenly over the entire edge faces. The difficulty in controlling the action of paper and stucco will be better understood from a brief description of the process of manufacture which with but slight departures is common to the industry. For this reason it is not deemed necessary to disclose the structure of a plaster board machine since the following description will be well understood by those skilled in the art.

A plaster board machine consists primarily of a horizontal travelling belt. At the head end of the machine are located the paper and stucco feeding devices. The paper is fed continuously from rolls, so placed that one sheet is above the other as it passes between a pair of forming rolls spaced apart above and below the belt a distance equal to the thickness of the finished board. As the sheets travel toward the rolls, the stucco in a wet state is deposited onto the lower sheet and is spread to a uniform thickness as the paper and stucco pass through the rolls on the belt which is of such length as to give the stucco an opportunity to set before it is cut to lengths and dried.

In forming a folded or sealed edge, such as disclosed in Figure 1, suitable folding devices or horns are used, which are located just ahead of the forming rolls, and in the path of the margin of the travelling sheets. These folding horns are shaped so as to bend or turn the margins inwardly as the stucco spreads between the folds. To prevent the stucco from spreading beyond the edge and to form a square edge, side dams as they are called, are located in line with the edges of the board, and coact with the folding horns to square the edge of the board and to gauge its width.

Owing to the nature of the materials, which are in more or less unstable condi-

tion, it is a difficult matter to produce a perfectly square or uniform edge since, as before explained, the paper does not bend at a sharp angle, nor is it always possible to bend back sheets of paper along the same line. As a result therefore, the edge, which approximates a straight and square edge, may be slightly out of square, as one sheet will be more rounded than the other, any one of these variations occurring in a relatively short length of the product.

To remedy this, and at the same time attain the desired results, it is proposed to subject the edges of the board to a grinding process. This may be done either during or after the manufacturing process; that is to say,—while the board is travelling on the belt, and after it has set, or after the board has been dried. The latter method appears to be the more practical, however, since the board is then hard and in better condition for grinding.

For the purpose of illustration an inclined section of delivery track is shown in Figure 1, along which the boards are advanced from the drying apparatus. Beyond the inclined section is a straight track section or extension.

The track sections are made of structural steel frame work, with parallel side frames 3—3, spaced apart at substantially the same distance as the boards extending transversely and at intervals are rollers 4 journaled at their ends in the side frame members.

Near the delivery end of the track are located grinding elements 5—5, consisting of grinding wheels 6—6, of a suitable abrasive material mounted directly on the armature shaft of motors 7—7. These grinding elements are accurately positioned in transverse alignment with each other on opposite sides of the track, with the plane of the grinding wheels at right angles to the edges of the boards. In such position the peripheries of the wheel extend inwardly beyond the side frame members, and for this reason, portions as at 8—8, are cut away.

The details of the grinding elements are clearly shown in Figures 6 and 7. The motors being fixed to a suitable bracket 9—9 adapted to have sliding connection with a beam or flanged cross member 10, extending beneath the rollers. In this way the grinding elements may be adjusted and set to the desired distance between the grinding faces and thus govern the final width of the finished boards.

Figures 5 and 6 also show a length of plaster board A being advanced along the track and between the grinding wheels 6—6, the latter being driven at a relatively high rate of speed, and in a direction such that the grinding cut is downward, although this is not essential. Figure 7 shows more clearly the nature of the grinding operation, the

face of the wheel being slightly rounded so that the cutting is gradual to the full depth of the material removed, as the board is advanced between the grinding wheels. It is desirable that the wheels be of relatively large diameter not only to secure high peripheral speed, but also to reduce to a minimum the tendency of a hollow ground edge being formed. Moreover, it is important to set the grinding wheels so that the plane of the board coincides with a horizontal plane passing through the axis of the wheels, and thus avoids the grinding of the board to a beveled edge.

Assuming that the width of the finished board is 36 inches, the machine would be set so that the initial product is say, $36\frac{1}{4}$ inches. Thus, if the distance between the faces of the wheels is set at 36 inches, it follows that $\frac{1}{8}$ of an inch of the material is removed from each edge of the board by the grinding wheels. The amount removed may vary, but it is the purpose to remove sufficient of the edge to include the thickness of the paper which extends over the face and a sufficient amount beyond so as to include the bends in the paper at the point where it folds over the edge as well as the point where it enters the stucco. In other words, it is the function of the grinding wheels to remove a substantial portion of the edge including all of the paper at the edge, thus completely severing the embedded margins from the top and bottom sheets, the same becoming strips $2^{\frac{1}{4}}$ extending along the edges which serve to reinforce the stucco which is wholly exposed.

Moreover, any unevenness in the edge or slight variations in width is overcome with the result that the board leaves the point of grinding with a perfectly true and square edge.

It follows therefore that the process herein set forth departs from any thought of protecting the edge by a covering of paper, since any advantage that might be gained by the partial covering in the initial forming of the edge, is deliberately sacrificed in favor of what is considered of greater importance, namely, a product of uniform width and a perfectly true edge, together with a suitable reinforcement, to prevent the stucco from cracking, and to provide an edge through which nails can be driven without injury to the board.

I consider the grinding process as the only practical method of obtaining the re-

sults set forth, inasmuch as cutting or trimming the board by other means does not insure either the smoothness of surface or the degree of uniformity required for making a perfect joint.

Having set forth the process embodying the invention, I claim:

1. The process of manufacturing plaster board consisting of introducing stucco in its wet state between sheets of covering material, forming a composite material of predetermined thickness and of approximately predetermined width, and grinding the edges of the formed material to an exact predetermined width.

2. The process of manufacturing plaster board, consisting of introducing stucco in its wet state between sheets of covering material, folding the margins of one of said sheets over the edge of the board and thence into the stucco, reducing the material to a predetermined thickness and passing the same between grinding wheels spaced apart at a predetermined distance to remove portions at the edge of the board including the portions of the sheet covering the same.

3. A process of treating plaster board having the marginal portions of the covering sheets folded over the edges and thence embedded in the plaster body, consisting of advancing the board between grinding wheels, thereby removing the material at the edges to a depth substantially equal to the thickness of the marginal portions of said covering sheets.

4. The process of treating plaster board having a covered edge, consisting of advancing such board lengthwise between grinding wheels to remove the edge covering and a portion of the material adjacent thereto.

5. The process of finishing plaster board, initially manufactured with a covered edge formed during the process of manufacture by folding the margins of the covering sheets over the edge of the plaster body and thence into said body between said cover sheets, consisting of advancing the boards lengthwise between rotative grinding wheels acting simultaneously on opposite side edges to remove the covering at the edge, and leaving the imbedded portions as reinforcing strips.

Signed at Port Clinton, O., this 16th day of Sept. 1925.

SIDNEY C. CLARK.
